BRACKET

Bernard M. Frenze, Garden City, N. Y., assignor
to American Fixture & Showcase Manufacturing Co., St. Louis, Mo., a corporation of Missouri

Application June 4, 1938, Serial No. 211,764

8 Claims. (Cl. 312—140.3)

This invention relates in general to display counters, tables, and the like, more particularly, my invention relates to, and resides in the provision of, a certain new and useful bracket of simple, durable, and inexpensive form and type, which may be conveniently installed upon and in connection with the display table or counter for facilitating both support upon the table or counter of merchandise retaining walls and illumination of the table or counter and merchandise displayed thereon.

And with the above and other objects in view, my invention resides in the novel features of form, construction, arrangement, and combination of parts presently described and pointed out in the claims.

In the accompanying drawing—

Figure 1 is a fragmentary perspective view of a display-counter or table equipped with a combination partition and lighting-fixture bracket constructed in accordance with and embodying my present invention;

Figure 2 is an enlarged perspective view of the bracket;

Figure 3 is an enlarged vertical sectional view of the bracket equipped counter or table, taken approximately along the line 3—3, Figure 1; and

Figure 4 is an enlarged horizontal sectional view of the counter or table, taken approximately along the line 4—4, Figure 3.

Referring now in more detail and by reference characters to the drawing, which illustrates a preferred embodiment of the present invention, the bracket is preferably in the form of a unitary casting A comprising a block or body-portion 1 provided with an axial recess 2 for receiving the tubular post or standard 3 of a suitable illuminating or light-fixture or the like 4, the recess 2 being formed centrally of its bottom wall with a co-axially bored channel 2' for accommodating an electric supply line 4' for the lighting-element 4" of the fixture 4, as best seen in Figures 1 and 3 and for purposes presently more fully appearing.

Adjacent its forwardly presented face 5, the body-portion 1 is widened for a portion of its height in the provision of a pair of laterally extending rectilinear flanges 6 and is machined to provide a smooth surface parallel to the axis of the recess or bore 2 and perpendicular to the transverse axis of the body-portion 1, as best seen in Figure 4 and for purposes presently more fully appearing.

Formed integrally with, and extending downwardly from, the body-portion 1, is an offset

flange 7 flush along its rear face with the rear face of the body-portion 1 and of substantially smaller transverse thickness than the body-portion 1, as best seen in Figure 3.

Also formed integrally with, and extending forwardly substantially at right angles from, the body-portion 1, is a foot-flange 8 having its under face flush with the under face of, and preferably throughout its length of substantially the same width as, the body-portion 1, the flange 8 being provided with a plurality of countersunk screw holes 9, all as best seen in Figure 1.

Detachably mounted, as by means of suitable screws s or other suitable attaching means, upon the front face 5 of the body-portion 1, and extending laterally beyond the opposite vertical margins of the flanges 6, is a rectangular face-plate 10 having a transverse dimension equal to the vertical height of the flanges 6, all as best seen in Figures 1 and 3 and for purposes presently more fully appearing.

In mounting the bracket upon a merchandise counter, table, or the like B, for instance, the counter-top 11 is mortised adjacent its rear margin, as at b, to snugly accommodate the foot flange 8, and the rear bin-wall 12 is vertically slotted or cut out, as at c, to accommodate the bracket body-portion 1, as best seen in Figure 2. The usual glass merchandise-retaining panels 13 of the table B are then slipped into the recesses 30 formed by the side faces of the flanges 6, the inner face of the plate 10, and the proximate surface of the bin-wall 12, all as best seen in Figure 2.

If desired, the plate 10 may be removed or detached to facilitate installation of the counter-panels 13 and may be adjusted for compensating for variation in partition thickness. By utilizing counter-panels 13 of slightly greater thickness than the flanges 6, the plate 10, when drawn tight by its holding screws, will securely retain the panels 13 in place.

Thus, simply and economically, though most efficiently, the bracket functions both as a support for the lighting-fixture 4 and a retaining-member for the panels 13.

It will, of course, be understood that the table B may be equipped with any desired number of the brackets A and that changes and modifications in the form, construction, arrangement, and combination of the several parts of the bracket may be made and substituted for those herein shown and described without departing from the nature and principle of my invention.

Having thus described my invention, what I

claim and desire to secure by Letters Patent is—

1. In combination with a counter having a top and a side-wall, the latter having a mortise, a bracket comprising a body-portion fitted in said mortise and having an axial bore for receiving an upright lighting-fixture, and a foot-flange extending forwardly from the body-portion disposed flatwise upon and secured to the counter-top.
2. In combination with a counter having a top and a side-wall, the latter having a mortise, a bracket comprising a body-portion fitted in said mortise and having an axial bore for receiving an upright lighting-fixture, an offset extending downwardly from the body-portion for engagement with a margin of the counter-top at said mortise, and a foot-flange extending forwardly from the body-portion over and secured to the counter-top.
3. In combination with a counter having a top and a side-wall, the latter having a mortise, a bracket comprising a body-portion fitted in said mortise and sized so that its front face is spaced forwardly from the front face of said counter-wall, said body-portion providing a seat for supporting an upright lighting fixture, means securing the bracket to the counter, and a plate secured flatwise to and upon the forward face, and extending laterally beyond a side margin, of said body-portion for co-operation with the counter-wall to support a panel.
4. A counter-display bracket comprising a body-portion having a recess for receiving an upright fixture-standard, an offset extension formed integrally with, and extending downwardly from, the body-portion for engagement with a counter, an integrally formed foot-flange extending forwardly from the body-portion at right angles thereto and being throughout its length of substantially the same width as said body-portion for engagement with a counter-top, and laterally extending flanges on, and having their front face flush with the front face of, said body-portion.
5. A counter-display bracket comprising a body-block for disposition in a counter-mortise, the block being recessed for upstandingly supporting a fixture-standard and sized so that its front face will be spaced forwardly from the

front face of the counter-wall in which it is disposed, and a plate mounted flatwise over said front face, and at a side margin extending outwardly beyond an adjacent side margin of the block for co-operation with the block and counter in the formation of a panel-receiving recess. 5

6. A counter-display bracket comprising a body-block for disposition in a counter-mortise, the block being recessed for upstandingly supporting a fixture-standard and provided at and adjacent its front margin with a laterally extending flange, and a plate mounted flatwise over the front face of the flange and block and at a side margin extending outwardly beyond an adjacent side margin of the flange for co-operation 10 with the flange and counter in the formation of a panel-receiving recess.

7. A counter-display bracket comprising a body-block for disposition in a counter-mortise, the block being recessed for upstandingly supporting a fixture-standard and provided at and adjacent its front margin with a laterally extending flange, a plate mounted flatwise over the front face of the flange and block and at a side margin extending outwardly beyond an adjacent 15 side margin of the flange for co-operation with the flange and counter in the formation of a panel-receiving recess, and a foot-flange extending forwardly from the block below said plate for engagement with the counter-top. 30

8. A counter-display bracket comprising a body-block for disposition in a counter-mortise, the block being recessed for upstandingly supporting a fixture-standard and provided at and adjacent its front margin with a laterally extending flange, 35 a plate mounted flatwise over the front face of the flange and block and at a side margin extending outwardly beyond an adjacent side margin of the flange for co-operation with the flange and counter in the formation of a panel-receiving recess, a foot-flange extending forwardly from the block below the plate for engagement with the counter-top, and a counter-engaging offset extending downwardly from the block at and adjacent its rear margin. 40 45
